US00D845113S

(12) **United States Design Patent** (10) **Patent No.:** **US D845,113 S**
Salter (45) **Date of Patent:** **** Apr. 9, 2019**

(54) **THERMAL EXPANSION TANK MOUNTING
BRACKET**

(71) Applicant: **Tony Richard Salter**, Conway, AR
(US)

(72) Inventor: **Tony Richard Salter**, Conway, AR
(US)

(**) Term: **15 Years**

(21) Appl. No.: **29/640,286**

(22) Filed: **Mar. 13, 2018**

(51) LOC (11) Cl. **08-05**

(52) U.S. Cl.

USPC **D8/371**
